UNITED STATES PATENT OFFICE

134,410

DESIGN FOR A SMOKING PIPE

Wallace Frederick, Stoutsburg, Mo.

Application April 14, 1942, Serial No. 106,571

Term of patent 7 years

To all whom it may concern:

Be it known that I, Wallace Frederick, a citizen of the United States, residing at Stoutsburg, in the county of Monroe and State of Missouri, have invented a new, original, and ornamental Design for a Smoking Pipe, of which the following is a specification, reference being had to the accompanying drawing, forming part thereof.

Figure 1 is a view in top plan of a smoking pipe embodying my new design.

Figure 2 is a view in side elevation.

Figure 3 is a view in bottom plan.

Figure 4 is a view in elevation of the bowl end of the pipe.

Figure 5 is a sectional view on the line 5—5 of Figure 2, and

Figure 6 is an elevational view as seen in the direction of the arrow.

I claim:

The ornamental design for a smoking pipe, as shown.

WALLACE FREDERICK.
